(57) **CLAIM**

We claim the ornamental design for movable barrier operator device, as shown and described.

DESCRIPTION

FIG. 1 is a bottom perspective view of the movable barrier operator device showing a first embodiment of our new design;

FIG. 2 is a top perspective view thereof;

FIG. 3 is a front elevation view thereof;

FIG. 4 is a rear elevation view thereof;

FIG. 5 is a bottom plan view thereof;

FIG. 6 is a top plan view thereof;

FIG. 7 is a right side elevation view thereof;

FIG. 8 is a left side elevation view thereof;

FIG. 9 is a bottom perspective view of the movable barrier operator device showing a second embodiment of our new design;

FIG. 10 is a top perspective view thereof;

FIG. 11 is a front elevation view thereof;

FIG. 12 is a rear elevation view thereof;

FIG. 13 is a bottom plan view thereof;

FIG. 14 is a top plan view thereof;

FIG. 15 is a right side elevation view thereof;

FIG. 16 is a left side elevation view thereof;

FIG. 17 is a bottom perspective view of the movable barrier operator device showing a third embodiment of our new design;

FIG. 18 is a top perspective view thereof;

FIG. 19 is a front elevation view thereof;

FIG. 20 is a rear elevation view thereof;

FIG. 21 is a bottom plan view thereof;

FIG. 22 is a top plan view thereof;

FIG. 23 is a right side elevation view thereof; and,

FIG. 24 is a left side elevation view thereof.

The broken lines in the drawings depict portions of the movable barrier operator device that form no part of the claimed design. The dash-dot-dash broken lines immediately adjacent to the shaded surfaces form a boundary of the claim and form no part thereof.

In the drawings, the stippled shading represents surfaces having the contrast in appearance shown.
